UNITED STATES PATENT OFFICE.

CLIFFORD DAILEY, OF NEW YORK, N. Y.

DESIGN FOR A LOCKET.

42,387.

Specification for Design.

Patented Apr. 9, 1912.

Application filed January 24, 1912. Serial No. 673,262. Term of patent 7 years.

To all whom it may concern:

Be it known that I, CLIFFORD DAILEY, a citizen of the United States, and residing at the city of New York, borough of Brooklyn, in the county of Kings and State of New York, have invented a new, original, and ornamental Design for Lockets.

Reference is to be had to the accompanying drawing, in which the figure is a view

showing my locket in elevation and in open position.

I claim:

The ornamental design for a locket, as shown.

CLIFFORD DAILEY.

Witnesses:

ERNEST TARKIER,
W. S. ORTON.
